UNITED STATES PATENT OFFICE.

JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

LATCH MECHANISM.

Application filed November 16, 1925. Serial No. 69,244.

This latch mechanism finds its utility in connection with automobile bodies of the closed body type. In bodies of this type, it is desired that there be provided the very maximum width of window pane in the door consistent with adequate strength of the door frame and further that the width of the door posts also be reduced to the minimum consistent with strength. The view of the occupants of the car is thereby obstructed to the least possible degree, and at the same time, the weight of the car is maintained at the minimum consistent with other advantages obtained. Various devices have been proposed for this purpose, a number of them by myself. The present mechanism lies in this field of invention.

Its principal aim is to avoid weakening of the jamb rail of the door opposite the latch mechanism, this weakening having been found to be a disadvantage of a number of inventions made for the purpose. Ancillary objects are the simplification and cheapening of the latch, and the simplification of the mechanical movements of its parts, with their resultant improvement in the ease of operation of the latch and a reduction of the wear and tear imposed by continuous usage.

These advantages and others which will be more fully apparent upon an understanding of my invention and are therefore best recited at the close of this specification, I attain by organizing the latch mechanism to embody an interlocking device between the inside and outside latch operating mechanisms which characterize this type of latch, upon the door post in such manner as to partake of movement in the vertical plane as distinguished from movement in the horizontal plane. Certain other movements have been tried when interlocking devices of this character have been mounted upon the post. I prefer to make this interlocking device, when so mounted upon the post and given this characteristic movement, in such form as to constitute it also the keeper of the latch mechanism, that is, that part of the latch mechanism which coacts with the latch bolt to effect latch engagement. With the interlocking device of the mechanism so embodied, the remaining parts of the latch mechanism and the mechanical movements thereof become remarkably simple.

One embodiment of my invention is shown in the accompanying drawings, in which

Fig. 1 is a horizontal section of the latch mechanism at large;

Fig. 2 is a three-quarter front perspective view of the interlocking member as mounted on the post;

Fig. 3 is a perspective view of the inside latch operating mechanism and

Fig. 4 is a similar view of the outside of the latch operating mechanism, in each of the latter instances shown in connection with the jamb rail of the door in connection with which the mechanism is mounted.

The jamb rail of the door is designated by numeral 10 and is of pressed metal construction of a form, at the latch, commonly known as a double-Z section. In this form, the main body of the rail is of a single thickness of stamped metal and comprises two transversely extending portions, the one 11 and the other 12, interconnected by a middle, longitudinally extending portion 13 which latter constitutes a rabbit in the rail. At the opposite ends of the main body 10, 11, 12, are provided oppositely extending flanges 14 and 15 constituting respectively the door overlap adapted to close the crack in the door jamb and make a neat joint with the door post, and to serve as a means of support for the latch-board 16. Connected with the outer overlap 14 is the outer panel 17 of the door, and connected with the inner flange 15 are other devices beside the latch-board 16 (not shown in the interest of brevity and clearness).

The opposite rail of the door, the hinge rail, is of somewhat similar, though simplified, construction, and it is not shown herein since it enters only indirectly into the combination of the present invention.

Within the body of the door is mounted the extensible member 18 in the form of the transparent window-pane, adapted to close the window of the door when in raised position. This window-pane is adapted to be raised and lowered by any of the usual mechanisms. Its width is substantially the full width of the body of the door. Its side edge 19 is arranged to slide in proximity to the face of the jamb rail 10 of the door. This is accomplished by mounting the extensible member 18 in a glass run channel 20 formed

by an angle strip 21 secured directly to the body 10 of the jamb rail and confining the extensible member 18 between itself and the rabbet section 13 of the jamb rail. The extensible member may, in such case, be truly said to lie over against the inner face of the jamb rail.

The door post is designated 22. It, too, is of pressed metal form and of channel cross-section. On the side wall of the channel cross-section is mounted the interlocking member 23. This interlocking member has a main body 24 disposed in the space between the jamb face of the rail 10 and the jamb face of the post 22. It is supported and guided by its projection 25 into a slot 26 formed in the side wall of the post. The projection 25 is secured to a vertically extending retaining bar 27 adapted for sliding engagement with the interior face of the side wall of the post, connection being made in this instance by screws 28 shown in Fig. 2. The slot 26 is elongated, but the sliding member 27 is still further elongated, whereby it not only retains the interlocking member 24 in place, but aligns it as well. The inner and outer ends of the interlocking member 24 project beyond the side walls of slot 26 and bear upon the outer face of the post whereby to provide more sliding bearings for the member. The ensemble is normally retained in its lower position by the spiral spring 29 bearing on the upper end of member 27 and confined in position by a tab 30 pressed out of the body of the bridge member 31 secured to the inner face of the side wall. The purpose of this bridging is primarily to retain the sliding member 27 in place should the interlocking member 24 be removed.

The opposite side of the post 22 is similarly provided with an aperture 26 and it is to be understood that a duplicate set of the parts described and to be described may be provided in connection with the opposite side of the post whereby two adjacent doors may be latched to the same post by shutting them toward each other.

The interlocking member 24 is of a form adapting it to constitute a keeper for the remainder of the latch mechanism now to be described. To this end, its outer portion 32 is of gently tapering form, adapting it for accommodation in the interior space 33 of the door jamb lying without the rabbet portion 13. The under side fits outer end and is chamfered upwardly at 32a for a purpose presently apparent. Its inner portion 34 tapers more abruptly, adapting it for more effective coaction with the latch bolt. This inner portion lies within the wider space 35 of the door jamb lying within the rabbet portion 13. By reason of the more generous space in this region, the parts may be given more generous proportions.

The inside and outside latch operating

mechanisms coact with this interlocking keeper. The inside latch operating mechanism is designated generally 36. It comprises a horizontal sliding latch bolt 37, the latch end 38 of which is projected through a slot in the body of rail 10 to coact with the inner end 34 of the keeper. The inner end 39 of the latch bolt is bifurcated to straddle the pivot pin 40 and block 41 which mount the vertically extending lever 42. Between the inner end of the bifurcation of the bolt 37 and the block 41 is confined a bolt spring 43 which biases the bolt outwardly at all times to the limit permitted by stop 43a. The lever 42 is a bell crank lever having an upper arm 44 adapted for the reception of a handle (not shown) and a lower arm 45. The lower arm is projected through an elongated slot 46 in the body of the jamb rail 10 and underlies the inner end 34 of the interlocking keeper 24. The bottom of slot 46 limits the downward movement of the arm 45 under the pressure of the spring 29 which forces the keeper 24 to its lower position and thus prevents this lever from returning. Spring 47a holds the arm 45 down when the door is open. Tabs 47 struck from base plate 48 are guides above and below pivot 40. The base plate 48 is, as shown, mounted in the angle between the branch 12 of the jamb rail and the inner flange 15. Any suitable means of mounting may be used.

The outer latch operating device is designated generally 49. Its base plate 50 comprises a main body substantially parallel to the outer panel of the door and two transversely bent flanges 51 and 52. The branch 52 is secured to the portion 11 of the jamb rail 10 to mount the base in position. Its reversely inner end 53 confines between it and the flange 52, a vertically reciprocable slide 54. This slide is provided on its outside with a lug 55 underlying the outer end 32 of the interlocking member 24, and connected with the body 54 of the slide through an elongated slot 56 whereby the slide may partake of the vertical movement necessary to effect vertical movement of interlocking device 24. Slide 54 is also provided with an inwardly extending lug 57, in this case projected through correspondingly elongated slot 58 in the reversely bent branch 53 of the flange 52.

This inner lug 57 is engaged by the oscillating arm 59 of the oscillatable spindle 60 journaled in the reversely bent flange 51 and base plate 50 and connected exteriorly with the handle 61 on the outside of the door.

So organized, the parts operate as follows: It being desired to open the door from the outside, the handle 61 is grasped and rotated counter-clockwise (in the embodiment shown in the drawing). Arm 59, engaging lug 57, translates its movement of oscillation

tion into a movement of vertical reciprocation of the slide 54. This, in turn, through the lug 55, imparts a vertical movement to the interlocking keeper 24. Through such movement, the inner bolt engaging end 34 of the keeper is elevated clear of the bolt 37 of the inner mechanism 36 without imparting any movement whatever to this bolt. The latch disengaging movement is therefore independent of that bolt. The door may then be swung open. Upon the release of the handle 61, the spring 60^a, and gravity or either of them return the slide 54, the oscillating arm 59 and the handle 61 to normal position against the stop 62 provided to prevent excessive reverse movement of the handle 61.

It being desired to open the door from the inside, the lever 44 is grasped and moved counter-clockwise to oscillate the arm 45 upwardly. This, through its engagement with the inner end 34 of the interlocking member 24, also raises the interlocking member in the vertical plane likewise freeing it from engagement with the bolt 37 without movement of that bolt whereupon the door may be pushed open. Upon release of lever 44, it is returned by gravity to its normal position, or a light spring 44^a may be used for that purpose. A similar light spring may be used in connection with the operating handle 61, so that when these parts are free from the biasing pressure which the spring 29 imposes on the interlocking member 24, they are retained in determinate normal position.

When it is desired to close the door after either of such openings, one has only to push it to closed position. So pushing the bolt 37 ratchets past the inner end 34 of the interlocking keeper 24 (now restored to its normal position) and into the latch engaging position shown in full lines in Fig. 1. In the movement of closing, the arm 45 of lever 42 and the lug 55 of the slide 54 successively pass beneath the under side of the interlocking keeper 24. Such passage is without interference since the under side of this keeper is upwardly inclined at its outer end 32^a to permit an easy entry of the parts 45 and 55 without interference, and at such elevations as to bring into play the spring 29. If desired, however, the small biasing springs mentioned with each of the inner and outer latch operating devices, may retain the parts 45 and 55 normally in such lowered positions that they do not engage the under side of the interlocking keeper until the handles 61 and the lever 44 respectively have been operated.

The latch mechanism of my invention contains but few parts, the latch engagement is generous, and the operation of the entire mechanism certain and sure. The advantages initially set forth are attained in the

full degree sought. Those modifications of my invention not departing from its generic spirit are intended to be comprehended by the attached claims as well as the embodiment herein shown.

I claim—

1. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, an interlocking device extending from one latch operating device to the other adapted to be carried by the door post, and partaking of movement in the vertical plane in its interlocking function.

2. A latch mechanism for an automobile door adapted to have an extensible portion of substantially the full width of the door slidably arranged in said door comprising inside and outside latch operating devices on opposite sides of the projected path of movement of said extensible member, an interlocking device extending from one latch operating device to the other and serving the purpose of a latch keeper adapted to be carried by the door post and partaking of movement in the vertical plane in its interlocking function.

3. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to be carried by the door post and partaking of a sliding movement in its interlocking function.

4. A latch mechanism for an automobile door adapted to have an extensible portion of substantially the full width of the door slidably arranged in said door, comprising inside and outside latch operating devices on opposite sides of the projected path of movement of said extensible member, an interlocking device serving the purpose of a latch keeper extending from one latch operating device to the other and adapted to be carried by the door post and to partake of movement in the vertical plane in its interlocking function, and a latch bolt coacting with said keeper independently of the latch operating devices.

5. A latch mechanism for an automobile door adapted to have an extensible portion of substantially the full width of the body

- of the door arranged for slidable movement therein with the side edge thereof in close proximity to the jamb face of the door, comprising inside and outside latch operating devices on opposite sides of the projected path of movement of said extensible member, an interlocking device partaking of movement in the vertical plane in its interlocking function extending from one latch operating device to the other and adapted to be carried by the door post, said interlocking device being biased in one direction by spring pressure and coacting with said latch operating devices to effect its movement in the opposite direction. 65
- 5 6. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to be carried by the door post and partaking of movement in the vertical plane in its interlocking function, one of said latch 70 operating devices embodying an oscillatable member effecting an operative connection with the interlocking device through a member which translates said oscillatory movement into a reciprocating movement. 75
- 10 7. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to be carried by the door post, said latch operating devices embodying vertically moving members engaging the interlocking 80 device to effect movement thereof in the vertical plane. 85
- 15 8. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to be carried by the door post and partaking of movement in the vertical plane 90 in its interlocking function, said latch operating devices independently coacting with the interlocking device. 95
- 20 9. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to be carried by the door post and partaking of movement in the vertical plane 100 in its interlocking function, said interlocking device being in the form of a keeper coacting with said latch bolt, and said keeper and said latch bolt partaking of relative horizontal movement to effect latch engagement and relative vertical movement to effect latch disengagement. 105
- 25 10. A latch mechanism for an automobile door adapted to have an extensible portion of substantially the full width of the body of the door arranged for slidable movement therein with the side edge thereof in close proximity to the jamb face of the door, comprising a latch bolt fixed in vertical position, inside and outside latch operating devices on opposite sides of the projected path of movement of said extensible member, and an interlocking device extending from one latch operating device to the other adapted to be carried by the door post and partaking of a sliding movement in its interlocking function, said interlocking device being in 110 the form of a keeper coacting with said latch bolt, and said keeper and said latch bolt partaking of relative horizontal movement to effect latch engagement and relative vertical movement to effect latch disengagement. 115
- 30 11. A latch mechanism for an automobile door adapted to have an extensible portion of substantially the full width of the body of the door arranged for slidable movement therein with the side edge thereof in close proximity to the jamb face of the door, comprising inside and outside latch operating devices on opposite sides of the projected path of movement of said extensible member, and an interlocking device extending from one latch operating device to the other adapted to serve as a latch keeper and to have a vertical sliding movement upon the jamb face of a door post. 120
- 35 In testimony whereof I hereunto affix my signature.

JOSEPH LEDWINKA.
